UNITED STATES PATENT OFFICE.

LOUIS SCHWITZER, OF INDIANAPOLIS, INDIANA.

FAN CONSTRUCTION.

Application filed May 15, 1924. Serial No. 713,547.

This invention relates to a fan structure, particularly to that type commonly used in connection with internal combustion engines for cooling the same.

The object of the invention is to provide suitable and practical means for lubricating the bearing surface of the fan and causing a constant flow of lubricant therein.

The principal feature of the invention resides in the employment of impeller blades so curved and positioned with respect to each other as to carry the lubricant from the lubricant chamber contained within the housing toward the center thereof so as to discharge it between the bearing surfaces of the hub and spindle, and creating enough pressure for causing it to be forced between the bearing surfaces to the opposite end thereof.

The full nature of the invention will be understood from the accompanying drawings and the following description and claims.

In the drawings, Figure 1 is a central vertical section taken through the hub and spindle of the fan structure. Fig. 2 is a section taken on the line 2-2 of Fig. 1.

In the drawings there is shown a stationary or fixed spindle 10 adapted to be rigidly secured on the front end of the motor in the usual manner. Rotatably mounted on the spindle there is a fan structure embodying a hub 11 provided at its forward end with an outwardly extending flange 12. Said flange is cupped so as to provide about its outer periphery a forwardly extending portion 13 against the forward edge of which a fan plate 14 securely fits by the bolts 15. The fan plate 14 is provided with the usual heads 16 to which the fan blades 17 are secured. Surrounding the hub 11 there is a housing 18 provided about its periphery with the usual pulley construction 19 adapted to receive a belt for driving the housing, hub 11 and fan blades by reason of their being rigidly connected by the bolts 15. Said housing is spaced from the hub to provide a lubricant chamber 20 which may be filled with lubricant through an opening closed by the screw cap 21.

Positioned in the space between the hub flange 12 and the fan plate 14, there is an impeller of sufficient width to fit snugly in said space, said impeller comprising a plurality of curved impeller blades 22 adapt-

ed to extend outwardly adjacent the interior surface of the projecting portions 13 of the flange 12. Said impeller is further provided with a hub portion 23 which is fixedly secured against the end of the spindle by a bolt 24, which is shown in Fig. 1 in elevation. It will be obvious from the foregoing, that while the impeller remains stationary with the spindle, the fan hub, housing and fan plate may be rotated for cooling purposes. This will cause the relative rotation between the impeller on the one hand and the hub and housing on the other hand. The structure may also be reversed so that the housing remains stationary while the impeller is rotated, either type of fan structure embodying the same principle as this invention with respect to the relative rotation between the impeller and lubricant containing housing.

Assuming the housing has been partially filled with lubricant 25, and the parts are given their relative movement, the rapid rotation of the hub and housing will cause the lubricant, by centrifugal force, to seek the outer portion of the chamber 20 and will cause it to spread so as to pass through a port 26 formed in the hub flange 12. As the impeller remains stationary while the hub and the port 26 rapidly rotate with respect thereto, the lubricant passing through said port will pass into what may be termed the curved passageways 27 between the impeller blades. As the port passes by the ends of the impeller blades, it will be closed, but will be opened as it passes between them so that the oil will be caused to flow into said passageways. The direction of curvature of the impeller blades and the intermediate passages 27 with respect to the rotation of the fan structure, is such as to cause the oil passing therein to be directed downwardly toward the center or the hub 23, from whence the oil is free to pass into an annular groove 28 formed in the flange 12, which groove is adjacent to and communicates with a longitudinally extending oil groove 29, which is shown herein as formed in the bearing surface of the hub 11. The pressure by which the oil is forced therein by reason of the rotation of the parts and the action of the impeller blades, would cause it to pass rearwardly, lubricating the bearing surface as it goes, until it reaches an annular groove 30 formed on the inner bearing surface at

the rear end of the hub 11. This groove will catch the oil and permit it to flow back into the chamber 20 through a port 31. Such oil as may pass beyond the annular groove 30 will be caught by a wire ring 32 which is firmly fixed about the spindle. This ring, which is spaced from the rear end of the hub, will deflect the oil upwardly therebetween into a deflecting cap 33, which will throw it back into the lubricating chamber.

Obviously it is immaterial to this invention as to what type of oil passage is provided longitudinally of the spindle, as the same may be shown herein or may be the usual spiral groove, either type of groove being equally effective, whether formed in the hub or spindle. Furthermore, such a groove may be altogether eliminated, depending upon the clearance of the bearing surfaces for permitting the oil to be forced rearwardly therebetween.

The invention claimed is:—

1. In a fan structure, a stationary member, a rotatable member adapted to rotate with respect thereto, one of said members having a lubricant chamber, an impeller mounted on one of said members, comprising

ing a plurality of curved impeller blades arranged so as to provide curved passageways therebetween, said passageways being in communication with the lubricant chamber at intervals during the relative rotation between said members, whereby lubricant may pass from said chamber into said curved passageways and be carried thereby to the bearing surfaces between said members for lubricating the same.

2. In a fan structure, a spindle, a hub rotatably mounted thereon, a lubricating chamber carried by said hub, a cup-shaped flange portion formed on said hub and having a lubricant passage therethrough, a fan plate secured to said hub as a closure for said cup-shaped portion, and an impeller completely filling said cup-shaped portion provided with a plurality of curved blades positioned therein and secured to the end of said spindle, the space between said blades forming curved passageways for receiving lubricant and causing the same to be forced inwardly to the bearing surfaces between said hub and spindle.

In witness whereof, I have hereunto affixed my signature.

LOUIS SCHWITZER.
